Primary Examiner — Austin Murphy(74) *Attorney, Agent, or Firm* — Goldberg Cohen LLP(57) **CLAIM**

We claim the ornamental design for a drying rack, as shown and described.

DESCRIPTION

FIG. 1 is an isometric top, right side view of a drying rack; FIG. 2 is an isometric bottom, right side view thereof; FIG. 3 is a top view thereof; FIG. 4 is a bottom view thereof; FIG. 5 is a left side view thereof; FIG. 6 is a right side view thereof; FIG. 7 is a front view thereof; FIG. 8 is a rear view thereof; FIG. 9 is a cross-sectional right elevation view thereof, the section being taken in a direction of section line 9-9 of FIG. 3; and

FIG. 10 is a cross-sectional left elevational view thereof, the section being taken in a direction of section line 10-10 of FIG. 3.

The broken lines in the drawings depict portions of the embodiments of the drying rack forming no part of the claim.
